UNITED STATES PATENT OFFICE

ALLEN B. COOKE, OF DANVILLE, ILLINOIS, ASSIGNOR TO UNITED AUTOGRAPHIC REGISTER COMPANY, OF CHICAGO, ILLINOIS, A CORPORATION OF ILLINOIS

AUTOGRAPHIC REGISTER

Application filed September 14, 1926. Serial No. 135,452.

My present invention relates to a machine for feeding or advancing a strip or strips of paper, and it has particular reference to a machine known as an autographic register in which the strips are intermittently advanced for each set of tickets to be discharged.

In structures of the above character the paper strips are provided with filing-pin or post-hole apertures that are arranged in two or more longitudinal parallel rows, and the normal feed members are roller disks that advance the strips along the lines of the apertures until a pair or set of apertures comes into registry with the feed roller members whereupon the normal feed devices become inoperative or ineffective upon the paper and the further advance thereof is arrested. When the next advancing operation is to take place some means in the form of a starter must be provided to initially advance the strips far enough to move the apertures out of registry with the normal feed members and then the latter will take hold and continue the advance of the next set of tickets. My present structure has to do with the starter or initial feed mechanism in combination with the normal feed mechanism, and it contemplates the employment of cam members or some similar structure that are opposed to each other during the initial feed of the strips and which, at a certain ratio or a differential of movement between the rotation of the respective initial feed members, do not come into opposition to each other until the advance of the strips has been arrested.

With my present structure I have provided a novel starter or initial feed mechanism that is positive in operation to advance the strips until the normal feed devices are out of registry with the apertures in said strips. My invention has numerous objects in view, among which are the provision of a feed mechanism for autographic registers that is novel in the form and arrangement of the parts, is simple in construction, is dependable in performing the several functions for which it has been designed, and which is economical to manufacture. I pre-

fer to accomplish the divers objects and to carry out my invention in substantially the manner hereinafter fully described and as more particularly pointed out in the claims, reference being herein made to the accompanying drawings that form a part of this specification.

In the drawings:—

Figure 1 is a vertical elevation of a portion of the operating side of my autographic register.

Figure 2 is a vertical elevation of the upper portion of the side of the register opposite that shown in Figure 1.

Figure 3 is a vertical transverse section of the register, the view being taken on broken line 3—3, Figure 4, and looking in the direction of the arrows.

Figure 4 is a top plan of the portion of the register illustrated in Figures 1 and 2 with the upper feed devices removed.

Figures 5, 6, 7, 8 and 9 illustrate the relative positions of the upper feed members with respect to the lower feed members during the differential of movement of the respective parts, in each view the lower members having been rotated one complete revolution after the position shown in the preceding view.

Figure 10 is a plan on reduced scale of a blank form of strip such as used in this apparatus.

The drawings are, in a sense, merely schematic for the purpose of illustrating a preferred or typical embodiment of my invention, and in said drawings, I have designated the same parts by similar reference characters wherever they appear throughout the several views.

The webs of material used in autographic registers of this character each consists of a strip 15 (Fig. 10) that is provided with spaced parallel rows of longitudinal apertures or filing-pin holes 16 that are preferably, arranged in pairs between the successive tickets that are printed on the strip, and, as will hereinafter more fully appear, these apertures are utilized by parts of the apparatus to control the advancement of the strip and to register the superposed tickets,

as well as for the purpose of filing and storing the tickets. The strips are placed in the machine either in roll or pad form and may be either rolled or folded together or in single sheets as desired.

- 5 The casing of the register is of the usual type, consisting of vertical longitudinal side-walls 17 that arise from opposite longitudinal edges of a base, and said walls are connected along a certain portion of their edges by a writing bed plate or platen 18. The mechanism for controlling the advancement of the strips preferably consists of upper and lower feed roller shafts 19 and 20 the former of which is journaled in a lift-frame 21 hinged at one end to ears 22 at the side of the casing to permit the same being raised when threading or inserting the paper strips originally into the register and the lower shaft is journaled in the side-walls of the casing in vertical alinement below the shaft 19. In front of these feed shafts there is a drive-shaft 23 that has its ends extended through the side-walls of the casing and one end has an operating handle or crank 24 secured to it. A gear 25 is secured to the extended opposite end of the drive-shaft, which gear is in mesh with an intermediate or idle-gear 26 that is rotatably mounted upon a stud projecting from the side-wall of the casing, and said idle-gear meshes with and drives a pinion 27 upon the adjacent end of the lower feed shaft 20. The proportions of the gears of this gear train are such that the feed shaft 20 rotates faster than the drive shaft 23. These shafts 19 and 20 are components of the upper and lower feed members that are adapted to both normally and initially advance the superposed strips through the autographic register, and the ends of said shafts opposite the pinion 27 are operatively connected together by the respective gears 28 and 29, the former of which is of less diameter than the latter so that the upper feed shaft and the elements mounted thereon will be moved at a higher speed and will rotate a greater number of times than the lower shaft 20 and the elements thereon.
- 50 Opposing upper and lower normal feed roller members in the form of complete disks 30 and 31 are secured to the respective feed shafts 19 and 20, and said members are spaced apart on their shafts a distance corresponding to the space between a pair of filing apertures 16 in the strips, and it will be noted that the disks are less in thickness than the diameter of the strip apertures which will cause the arrest of the strip advancement whenever a set of these apertures comes into registration with the opposed disks. The advancement of the strips is arrested at the end of each set of tickets being fed through the machine so that the 55 normal advancement and the initial advance-

ment take place intermittently. The diameters of the upper and lower feed roller members 30 and 31 differ from each other in the same ratio as the differences in diameter of the gears 28 and 29 which will permit the roller members to feed the strips uniformly when engaging the latter outside the apertures.

When the feed roller members have become registered with the filing apertures 18 in the strips said members are inactive or inoperative to advance said strips until the latter have been moved slightly ahead by starter devices or initial feed elements which will now be described. Projecting so radially from the feed shafts 19 and 20, and preferably formed integrally with said shafts are upper and lower lugs or blocks 32 and 33 respectively. I have illustrated three sets or pairs of these elements, a central pair located intermediately of the spaced feed roller members 30 and 31, and a pair between the respective feed roller sets and the walls of the casing. These lugs or blocks have concentric outer faces 32^a and 33^a that are curved upon the same radial diameters as those of the feed roller members 30 and 31, and they respectively project from the shafts the same distance as said members. The rotational movements of the feed-shafts 19 and 20 are so timed that the respective lugs or blocks 32 and 33 will be opposite or engaging each other, but once during a plurality of revolutions. This will occur some time after the feed roller members come into registry with the strip apertures, and for clearness it may be here stated that the upper shaft 19 revolves eight times to five revolutions of the lower shaft 20.

105 The driving mechanism of the apparatus is so controlled that the rotation of the crank-handle 24 is stopped at the time the peripheries of the elements come into engagement with each other, and to do this I provide a stop-cam 34 mounted upon the extended end of a driven cam-shaft 35 that has its ends projected through the walls of the casing. This stop-cam 34 is adapted to be engaged by a pin 36 projecting from a trigger 37 that is pivotally mounted on the crank-handle and said trigger is maintained in its normal position by means of a coiled contraction spring connected thereto and to an adjacent portion of the crank-handle. The cam-shaft 35 has a gear 38 secured to its opposite extended end, which gear meshes with and is actuated by a pinion 39 on the drive-shaft next to the gear 25. The gear 38 is double the size of pinion 39 so that the cam-shaft 35 makes but a single revolution during two complete revolutions of the drive-shaft, which will thus permit the pin 36 to clear the projecting portion of the cam during the first revolution of the 110 cam-shaft 35. The cam-shaft 35 is supported by a bearing 40 mounted in the side-walls of the casing, and the drive-shaft 23 is supported by a bearing 41 in the side-walls of the casing. The drive-shaft 23 is supported by a bearing 42 in the side-walls of the casing, and the drive-shaft 23 is supported by a bearing 43 in the side-walls of the casing. The drive-shaft 23 is supported by a bearing 44 in the side-walls of the casing, and the drive-shaft 23 is supported by a bearing 45 in the side-walls of the casing. The drive-shaft 23 is supported by a bearing 46 in the side-walls of the casing, and the drive-shaft 23 is supported by a bearing 47 in the side-walls of the casing. The drive-shaft 23 is supported by a bearing 48 in the side-walls of the casing, and the drive-shaft 23 is supported by a bearing 49 in the side-walls of the casing. The drive-shaft 23 is supported by a bearing 50 in the side-walls of the casing, and the drive-shaft 23 is supported by a bearing 51 in the side-walls of the casing. The drive-shaft 23 is supported by a bearing 52 in the side-walls of the casing, and the drive-shaft 23 is supported by a bearing 53 in the side-walls of the casing. The drive-shaft 23 is supported by a bearing 54 in the side-walls of the casing, and the drive-shaft 23 is supported by a bearing 55 in the side-walls of the casing. The drive-shaft 23 is supported by a bearing 56 in the side-walls of the casing, and the drive-shaft 23 is supported by a bearing 57 in the side-walls of the casing. The drive-shaft 23 is supported by a bearing 58 in the side-walls of the casing, and the drive-shaft 23 is supported by a bearing 59 in the side-walls of the casing. The drive-shaft 23 is supported by a bearing 60 in the side-walls of the casing, and the drive-shaft 23 is supported by a bearing 61 in the side-walls of the casing. The drive-shaft 23 is supported by a bearing 62 in the side-walls of the casing, and the drive-shaft 23 is supported by a bearing 63 in the side-walls of the casing. The drive-shaft 23 is supported by a bearing 64 in the side-walls of the casing, and the drive-shaft 23 is supported by a bearing 65 in the side-walls of the casing. The drive-shaft 23 is supported by a bearing 66 in the side-walls of the casing, and the drive-shaft 23 is supported by a bearing 67 in the side-walls of the casing. The drive-shaft 23 is supported by a bearing 68 in the side-walls of the casing, and the drive-shaft 23 is supported by a bearing 69 in the side-walls of the casing. The drive-shaft 23 is supported by a bearing 70 in the side-walls of the casing, and the drive-shaft 23 is supported by a bearing 71 in the side-walls of the casing. The drive-shaft 23 is supported by a bearing 72 in the side-walls of the casing, and the drive-shaft 23 is supported by a bearing 73 in the side-walls of the casing. The drive-shaft 23 is supported by a bearing 74 in the side-walls of the casing, and the drive-shaft 23 is supported by a bearing 75 in the side-walls of the casing. The drive-shaft 23 is supported by a bearing 76 in the side-walls of the casing, and the drive-shaft 23 is supported by a bearing 77 in the side-walls of the casing. The drive-shaft 23 is supported by a bearing 78 in the side-walls of the casing, and the drive-shaft 23 is supported by a bearing 79 in the side-walls of the casing. The drive-shaft 23 is supported by a bearing 80 in the side-walls of the casing, and the drive-shaft 23 is supported by a bearing 81 in the side-walls of the casing. The drive-shaft 23 is supported by a bearing 82 in the side-walls of the casing, and the drive-shaft 23 is supported by a bearing 83 in the side-walls of the casing. The drive-shaft 23 is supported by a bearing 84 in the side-walls of the casing, and the drive-shaft 23 is supported by a bearing 85 in the side-walls of the casing. The drive-shaft 23 is supported by a bearing 86 in the side-walls of the casing, and the drive-shaft 23 is supported by a bearing 87 in the side-walls of the casing. The drive-shaft 23 is supported by a bearing 88 in the side-walls of the casing, and the drive-shaft 23 is supported by a bearing 89 in the side-walls of the casing. The drive-shaft 23 is supported by a bearing 90 in the side-walls of the casing, and the drive-shaft 23 is supported by a bearing 91 in the side-walls of the casing. The drive-shaft 23 is supported by a bearing 92 in the side-walls of the casing, and the drive-shaft 23 is supported by a bearing 93 in the side-walls of the casing. The drive-shaft 23 is supported by a bearing 94 in the side-walls of the casing, and the drive-shaft 23 is supported by a bearing 95 in the side-walls of the casing. The drive-shaft 23 is supported by a bearing 96 in the side-walls of the casing, and the drive-shaft 23 is supported by a bearing 97 in the side-walls of the casing. The drive-shaft 23 is supported by a bearing 98 in the side-walls of the casing, and the drive-shaft 23 is supported by a bearing 99 in the side-walls of the casing. The drive-shaft 23 is supported by a bearing 100 in the side-walls of the casing, and the drive-shaft 23 is supported by a bearing 101 in the side-walls of the casing. The drive-shaft 23 is supported by a bearing 102 in the side-walls of the casing, and the drive-shaft 23 is supported by a bearing 103 in the side-walls of the casing. The drive-shaft 23 is supported by a bearing 104 in the side-walls of the casing, and the drive-shaft 23 is supported by a bearing 105 in the side-walls of the casing.

crank and will stop the rotation of said shaft at the end of the second revolution.

After a ticket has been made out by the operator, he releases the trigger device from the stop-cam, or stop-arm, with which the 5 rotatable stop-shaft is equipped, and then rotates the crank. This causes the strips to be advanced initially by the initial-feed blocks, or segments, (which are in gripping engagement) and the feeding of the strips 10 is then continued by the normal feed-disks, or feed-rollers, until the feed-disks encounter the apertures, whereby the further advance of the strips is arrested. The operator continues to rotate the crank until 15 it is arrested by the trigger device engaging the stop-arm carried by the rotating stop-shaft. During the feeding of the strips by the main feed-disks, the starter-blocks 20 do not come into cooperative relation again until the moment before the feed is arrested, at which moment the feed-blocks, or segments, grip the strips in readiness to start the advance thereof as soon as the 25 crank is again rotated to perform the next feeding operation. Thus, holding the paper strips between their coacting surfaces, the blocks are in readiness to advance the strips a sufficient distance to permit the main feed-disks to take hold and continue the feed.

In the construction described, the main feed-disks 30 and 31 have different radii, but have the same surface speed; and the initial-feed segments 32 and 33 have the 30 same radii, respectively, as the feed-disks 30 and 31, and all of the members have the same surface speed. All of these members have a common driving means actuated by the crank 24, and the commonly used clutch-controlled initial-feed device is rendered unnecessary.

The improved feed-mechanism described and claimed herein is particularly well adapted for use in a register operating upon the principle described in my co-pending 45 application 135,451, filed of even date herewith.

The foregoing detailed description has been given for clearness of understanding 50 only, and no unnecessary limitations should be understood therefrom, but the appended claims should be construed as broadly as permissible, in view of the prior art.

What I claim is:—

55 1. In an autographic register, means for normally feeding an apertured paper strip, which means include upper and lower rotatable shafts and feed roller members mounted thereon to engage the strip and 60 which become ineffective to advance the strip upon registration with strip apertures, and initial feed mechanism consisting of feed members fixed on said shafts and adapted to intermittently engage the strip, and 65 means for rotating said shafts at different

speeds whereby one of said initial feed members describes a plurality of revolutions before being in coactive relation with its companion member.

2. The combination with the normal feed devices of an autographic register including upper and lower feed shafts, of an initial feed mechanism comprising strip engaging members mounted upon said shafts and adapted to be positioned in coactive strip advancing relation to each other after a plurality of revolutions, means for imparting a differential of movement to said shafts to cause said members to engage the strip when said normal feed devices become inoperative to advance the strip, a crank for rotating said shafts, and releasable devices for arresting the movement of said crank when said strip engaging members initially engage the strip between them.

3. The combination with the normal feed devices of an autographic register including upper and lower feed shafts, of an initial feed mechanism comprising strip engaging members mounted upon said shafts and adapted to be positioned in coactive strip advancing relation to each other after a plurality of revolutions, a rotatable drive-shaft geared to and actuating said feed shafts, a crank secured to said drive-shaft, a stop-cam rotatable at a slower speed than said drive-shaft, and a trigger structure adapted to predeterminedly engage said stop-cam to arrest the rotation of said drive-shaft when said initial feed members come into coactive relation with the strip.

4. In an autographic register, normal feed members adapted to become inactive to advance the strips upon engagement with apertures therein, initial feed members adapted to advance the strips when the normal feed members are inactive upon the strips, a crank for rotating said feed members, and releasable devices for arresting the movement of said crank when said initial feed members come into engagement with the strips.

5. In an autographic register, normal feed members adapted to become inactive to advance the strips upon engagement with apertures therein, initial feed members adapted to advance the strips when the normal feed members are inactive upon the strips, a rotatable drive-shaft operatively connected to said feed members, a crank secured to said shaft, a stop-cam rotatable at a slower speed than said drive-shaft, and a device on said crank adapted to predeterminedly engage said stop-cam to arrest the rotation of said drive-shaft when said initial feed members come into co-active relation with the strips.

6. In means of the character set forth, means for feeding an apertured strip, comprising a pair of shafts having different

speeds of rotation, said shafts being equipped with main feed-disks adapted to work idly when an aperture is encountered, and initial-feed segments rotating with said shafts and coming into feeding relation intermittently to effect initial feed of the strip.

7. In means of the character set forth, strip-feeding mechanism, comprising a pair of main feed-disks adapted to feed the strip a predetermined distance and then to work idly, a pair of continuously rotating initial-feed segments which have different periods of rotation but approximately uniform surface speeds and which come into feeding relation after one of said segments has made a plurality of rotations, and a common driving means for said disks and segments, whereby, in the actuation of the main feed-disks, the initial-feed segments will advance the strip initially into position to be fed by the main feed-disks.

8. In means of the character set forth, strip-feeding mechanism comprising a pair of main feed-disks adapted to engage apertures in the strip at the conclusion of a feeding operation, a pair of initial-feed segments adapted to operate idly during the main feeding operation and to come automatically into feeding relation to initiate the successive feeding operations, driving means for actuating said feed-disks and segments, and a stop-device automatically arresting said driving means after the conclusion of each feeding operation.

9. In means of the character set forth, strip-feeding mechanism comprising a pair of main feed-disks adapted to engage apertures in the strip at the conclusion of a feeding operation, a pair of initial-feed segments adapted to operate idly during the main feeding operation and to come automatically into feeding relation to initiate the successive feeding operations, driving means for actuating said feed-disks and segments, and a stop-device automatically arresting said driving means after the conclusion of each feeding operation, said stop-device comprising a releasable catch.

10. In means of the character set forth, strip-feeding mechanism comprising a pair of main feed-disks adapted to engage apertures in the strip at the conclusion of a feeding operation, a pair of initial-feed segments adapted to operate idly during the main feeding operation and to come automatically into feeding relation to initiate the successive feeding operations, driving means for actuating said feed-disks and segments, and a stop-device automatically arresting said driving means after the conclusion of each feeding operation, said stop device comprising a rotating stop-arm and a releasable catch adapted to engage therewith after the conclusion of the feeding operation.

11. In means of the character set forth,

strip-feeding mechanism comprising a pair of shafts geared to rotate at different speeds and having mounted thereon to rotate therewith main feed-disks of different radii but having the same surface speed and also intermittently registering initial-feed segments having the same radii as the corresponding feed-disks, and driving means for actuating said shafts.

12. In means of the character set forth, strip-feeding mechanism comprising a pair of shafts geared to rotate at different speeds and equipped with main feed-disks of different radii but having the same surface speed and equipped also with initial-feed segments having the same radii as the corresponding feed-disks, driving means for actuating said shafts, and a stop-device serving automatically to arrest said driving means after the feeding operation has been concluded and the initial-feed segments have been brought into cooperative relation.

13. In means of the character set forth, strip-feeding mechanism comprising a pair of shafts geared to rotate at different speeds and equipped with main feed-disks of different radii but having the same surface speed and equipped also with intermittently registering initial-feed segments having the same radii as the corresponding feed-disks, driving means for actuating said shafts, and a stop-device serving automatically to arrest said driving means after the feeding operation has been concluded and the initial-feed segments have been brought into cooperative relation, said stop-device including a rotating stop-arm, a crank, and a releasable catch.

14. In means of the character set forth, strip-feeding mechanism comprising a pair of shafts geared to rotate at different speeds and equipped with main feed-disks of different radii but having the same surface speed and equipped also with intermittently registering initial-feed segments having the same radii as the corresponding feed-disks, a crank-shaft geared to one of said first-named shafts and equipped with a crank-handle, a stop-shaft geared to said crank-shaft, and co-acting means on said crank-handle and stop-shaft for arresting the crank after the conclusion of the feeding operation.

15. In a register of the character set forth: normal-feed means comprising feed-disks adapted to become inoperative to feed the strips upon encountering perforations therein; initial-feed means comprising segments having different periods of rotation; and means for continuously rotating said feed-disks and said segments during a cycle of operations, said last named means being operative to bring said segments into co-operative feeding position at the conclusion of such cycle of operations after a period of idle operation of said feed-disks.

16. In means of the character set forth,

the combination with a main frame, a lower feed-shaft journaled therein, a frame-member having one end pivotally mounted on the main frame to swing in a plane transversely thereof, an upper feed-shaft journaled in the pivoted frame-member, normal feeding-disks pivoted on said shafts, initial feed-segments fixed on said shafts, intermeshing gears fixed on said shafts, and a plate spaced from said feed-shafts and aligned therewith.

10 Signed at Danville, in the county of Vermilion and State of Illinois, this 17th day of July, 1926.

ALLEN B. COOKE.
